UNITED STATES PATENT OFFICE.

WILLIAM E. NEWNAM, OF ST. LOUIS, MISSOURI, ASSIGNOR TO NATIONAL LEAD COMPANY, OF ST. LOUIS, MISSOURI, A CORPORATION OF NEW JERSEY.

FURNACE-CHARGING SYSTEM.

Application filed July 27, 1922. Serial No. 577,923.

To all whom it may concern:

Be it known that I, WILLIAM E. NEWNAM, a citizen of the United States, and residing at St. Louis, Missouri, have invented 5 the new and useful Improvement in Furnace-Charging Systems, of which the following is a specification.

This invention relates to furnace charging systems, and more particularly to systems adapted for charging lead smelting furnaces.

Lead smelting furnaces are of elongated form and it is necessary to charge the same periodically with ore, fuel and flux in the 15 proper proportions. As such furnaces must be kept in constant operation, not only is it necessary that the charging system be simple, but also efficient and reliable and at all times under control. The components 20 of the charge should also be properly mixed in the furnace.

One of the objects of this invention, therefore, is to provide a system whereby the components will be properly assembled and 25 deposited in the furnace.

Another object of this invention is to provide a system whereby the placement of the assembled charge in the furnace and the selection of components to make the charge is 30 under control of the superintendent.

Another object of this invention is to provide a system which is simple in construction and operation, and which is effective and reliable.

Further objects will appear from the detail description taken in connection with the accompanying drawings, in which:

Figure 1 is a plan of a system embodying this invention;

Figure 2 is an elevation;

Figure 3 is a detail showing one of the receiving or weighing devices;

Figure 4 is a section of one of the receiving or weighing devices;

Figure 5 is a similar view showing another receiving or weighing device;

Figure 6 is a side elevation of the gathering car;

Figure 7 is an end elevation of the charge car; and

Figure 8 is a diagram illustrating the relation of the several parts.

The drawings are diagrammatical in form, and no attempt has been made to 55 show details of construction, for as to these

details, any suitable known mechanism may be used well known to those skilled in the art.

Referring to the accompanying drawing, and more particularly to Figures 1 and 2, arranged along a suitable track 12 are a series of bins 10, 11, etc. which receive components of the charge which may be distributed in these bins in any suitable manner, as by cars running on overhead tracks 13 and 14; where the plant is one for the smelting of lead, the bins are charged with ore, fuel and flux. Thus, for example, in Figure 1, the first three bins 10, 11 and 20 may contain coke, bins 21 and 30 grey slag, 70 bins 31 and 40, dross, 41 and 50, grey slag, 51, gravel, 60, limestone and 61, iron cinder. The components of a charge can, however, be placed in the bins to suit the requirements or practice of the particular superintendent of the plant.

The track 12 runs in a sub-way 15 below the floor level of the bins and over this track extend a series of weighing devices 1, 2, 3, 4, 5 and 6 which, in the particular embodiment shown, are placed opposite alternate partitions of the bins. Each of these weighing devices has a pair of hoppers A and B, each of which has a multiple beam scale, as hereinafter described.

The track 12 extends underneath a sinter cake plant 16, such as the usual Dwight Lloyd apparatus, which is provided with outlet hoppers 17 and 18 discharging into weighing devices 7 and 8 which may be similar to the weighing devices 1 to 6 inclusive, as will be hereinafter more fully described.

The track 12 has a branch 19 on the same level and on which a gathering car 22 running on the track may be switched. This gathering car is arranged to run underneath the weighing devices 1 to 8 inclusive to receive the charge therein, as hereinafter described. Crossing the branch track 19 is an inclined track 23 which leads from a pit below the track 19 to the furnaces 24 and 25, and on this track is arranged to run a charge car 26. Accordingly the charge gathered by the gathering car from the several weighing devices is dumped into the charge car to a position therebelow, as shown in Figure 2. The charge car is then wheeled up the incline and over a selected furnace to dump the charge therein. For 110

this purpose, suitable cables may be provided or the cars may be operated electrically as is well known to those skilled in the art.

6 Referring now to Figures 3 and 4, the weighing device shown, as previously referred to, is in duplicate and comprises a pair of weighing hoppers 27, each of which has a scale 28. As shown, this scale is of the 10 multiple beam type having setting devices 29 so that each hopper may have weighed therein successively from one to four different components of the charge. Such multiple beam scales are well known in the art 15 and a further description thereof is, therefore, unnecessary.

Each hopper has drop bottoms 32 counter-weighted as shown at 33 and having suitable connections 34, whereby each hopper 20 may be dumped. In order to control the dumping of any hopper section, there is provided in the sub-way 15 a pair of levers 35 and 36, each of which controls the dumping of a hopper section and which are positioned to be operated by the driver of the gathering car or larry 22.

The arrangement of the hoppers and scales for the Dwight Lloyd apparatus is similar to those previously described for the 30 weighing devices 1 to 6 inclusive and the same parts are indicated by like reference characters. In this case, the hoppers 17 from the Dwight Lloyd apparatus discharge on belts 37 into the hoppers 27.

35 The gathering car is shown in detail in Figure 6 and comprises generally a pair of trucks 38 and a frame 39 thereon. This frame is provided with a hopper or body 42 which is provided with any suitable and 40 well known dumping bottom 43, but which is divided by transverse partitions 44 to divide the hopper or body into two distinct compartments, one at each end corresponding respectively to the hoppers of a weighing device. This truck may be electrically 45 driven and may be provided with suitable dumping devices which may, however, be of any suitable construction well known to those skilled in the art, and a further description thereof is, therefore, unnecessary.

50 The charge car comprises suitable running gear 45 provided with a frame 46 supporting a hopper or body 47 which, as in the case of the gathering car, is of elongated form and is also divided by a transverse partition 48 to form two compartments, one at each end. The bottom 49 of this charge car body is also of the drop type and any suitable dropping mechanism 55 is provided which may be of any suitable construction well known to those skilled in the art.

60 In the operation of the system embodying this invention, let us take, for example, that the device 1 is loaded with coke from

either bin 10 or 11, device 3 is loaded with grey slag and dross from bins 30 and 31, device 5 with grey slag from bin 50 and gravel from bin 51, and device 6 with limestone from bin 60 and iron cinder from bin 61. The material may be discharged from the bins into the weighing devices by gravity. As the gathering car now passes underneath the hoppers at the several assembling stations, the driver will successively, by the operation of the levers 35 and 36, dump the contents into the gathering car so that when the gathering car reaches the branch 19, it will be fully loaded with the components of the charge successively 70 dropped therein. As the gathering car is positioned over the charge car, the contents are dumped into the charge car and the latter is wheeled up the incline and the contents 75 dumped into the furnace.

80 It will be understood that in some cases a charge of the sinter cake from the Dwight Lloyd plant can be weighed into the charge car in a similar way, either alone or in connection with components from the materials 85 of the devices 1 to 6 inclusive. It will further be understood that a series of components may be placed in a single hopper 90 as the multiple beam scale provides for ready weighing of the same.

95 In the operation of the plant, no fixed rule need be followed as to the weighing hopper in which a given component is placed, as in practice this is governed almost entirely by the nearness of the weighing 100 hopper to the storage bin; the idea being to place the components from any such storage bin in the nearest weighing hopper in order to reduce the length of haul from the storage bin to the weighing hopper. It is not necessary that the components be bedded even 105 in the weighing hopper, as they can be placed at random therein by first drawing from the hopper of the lowest number containing the charge components and drawing successively from the other weighing 110 hoppers containing the charge components. The main purpose of the arrangement of the storage bins and weighing hoppers is to shorten the haul from the storage bins to 115 the weighing hoppers. Accordingly the same charge component can be stored in two or more storage bins, some times adjoining and sometimes remote from each other. By 120 employment of a series of weighing hoppers, when a charge component in one bin is exhausted, the same charge can be drawn from another bin located remotely from the exhausted bin and placed in the nearest weighing hopper, thus minimizing the haul from the storage bins to the weighing hoppers.

125 While, therefore, the components of the charge are often placed in different hoppers, such components are successively 130 picked up as the gathering car passes un-

derneath the same. This is not for the purpose of bedding the charge but for shortening the haul of any given component or components. As a matter of fact, one hopper will frequently be loaded with two components which are not bedded even in the weighing hopper.

Upon referring to Figure 8, it will be noted that the length or horizontal extent of the different hoppers, cars and furnace increase progressively. Thus, for example, the weighing hoppers 27 have a combined length of eight feet, the gathering car 22 has a length of nine feet, the charge car 26 has a length of eleven feet, while the furnace 25 has an inside measurement of twelve feet, three inches. Thus, it will be seen that the increase in horizontal extent or length from the weighing hopper to the furnace is over fifty percent. This is advantageous for as the charge is successively dropped from the weighing hopper to the gathering car, to the charge car, and into the furnace, this charge is progressively extended or spread out, thereby resulting in a better distribution and mixing of the charge. This mixing is finally accomplished in the furnace where the mixing is provided to cause the charge to spread outwardly toward the sides of the furnace as is required. The charge is, however, simply dropped from the weighing hopper to the gathering car and the charge car.

As previously pointed out, the weighing devices have duplicate hoppers and these correspond to the compartments of the gathering car and the charge car. Accordingly the charge is kept in two separate or parallel bodies, one at each end. Accordingly the delivery of the charge to the furnace can be selectively controlled, for example, if it is desired to vary the charge from one end of the furnace with respect to the other, either in quantities or in components, this can be readily accomplished by varying the delivery of the components of the charge to the weighing hoppers. Thus, where only one weighing hopper of a set is loaded, one end of the gathering car will be loaded heavier than the other, and in the same way, the quality and the proportion of the ingredients in the separate ends can also be varied.

In a plant of this type, it is very essential that the plant be kept in continuous operation. Accordingly the mechanism, such as the gathering and charge cars should be in duplicate. In order to provide for the charge car being duplicated, a reserve car 260 is kept on an elevated track 52 which has a switch 53 suitably controlled by a counter-weight 54 and hoisting cables 55, so that this switch 53 may be dropped down on the main cross track 23. This allows the reserve car to replace the regular charge car.

While this system has been described as

being particularly applicable to a lead smelting plant, it is obvious that many of its features are applicable to other plants, such as copper smelting plants which also use elongated furnaces. It is further obvious that various changes may be made in details without departing from the spirit of this invention; it is, therefore, to be understood that this invention is not to be limited to the specific details shown and described.

Having thus described the invention, what is claimed is:

1. In a system for charging elongated furnaces, a track leading to the furnace, a series of bins arranged along said track, a series of weighing hoppers arranged along said track, each hopper being positioned to receive material from a number of said bins, and a gathering car movable along said track and adapted to gather the material from said hoppers.

2. In a system for charging elongated furnaces, a track leading to a discharge point at the furnace, a series of bins arranged along said track, a series of weighing devices arranged along said track, each device having a number of hoppers positioned to receive the material from a number of said bins, and a gathering car movable along said track and adapted to gather the material from said hoppers.

3. In a system for charging elongated furnaces, a gathering track, a cross track leading to a discharge point at the furnace, a series of bins arranged along said gathering track, a series of weighing hoppers arranged along said gathering track and adapted to receive the material from said bins, a gathering car movable along said gathering track and adapted to gather the material from said hoppers, and a charge car on said cross track and receiving the material from said gathering car.

4. In a system for charging elongated furnaces, a track leading to a discharge point at the furnace, a series of weighing devices arranged along said track, each device having a number of hoppers adapted to receive the material, each hopper having means for delivering a series of components thereto and means for independently weighing a series of components therein, a gathering car movable along said track and adapted to gather the material from said hoppers, and means for independently controlling the dumping of said hoppers.

5. In a system for charging elongated furnaces, a weighing device comprising a number of hoppers, a gathering car adapted to receive the material from said device, said car having compartments corresponding to said hoppers, and a charge car of greater horizontal extent than said gathering car adapted to receive the material from said gathering car.

6. In a system for charging elongated furnaces, a weighing device comprising a number of hoppers, a gathering car adapted to receive the material from said device, said car having compartments corresponding to said hoppers, and a charge car adapted to receive the material from said gathering car, said charge car having compartments corresponding to the compartments in said gathering car.
7. In a system for charging elongated furnaces, a gathering car having compartments each of which is adapted to receive the material, and a charge car having compartments corresponding to the compartments in the charge car and adapted to receive the material therefrom.
8. In a system for charging elongated furnaces, a gathering track, a cross track leading to the furnace, a gathering car on said gathering track and having compartments each of which is adapted to receive the material, and a charge car on said cross track and having compartments corresponding to the compartments in the charge car and adapted to receive the material therefrom.
9. In a system for charging elongated furnaces, a receiving hopper for the material, a gathering car of greater horizontal extent than said hopper and adapted to receive the material therefrom, and a charge car of greater horizontal extent than said gathering car and adapted to receive the material therefrom.
10. In a system for charging elongated furnaces, a receiving hopper for the material, a gathering car of greater horizontal extent than said hopper and adapted to receive the material therefrom, a charge car of greater horizontal extent than said gathering car and adapted to receive the material therefrom, and a furnace of greater horizontal extent than said charge car and adapted to receive the material therefrom.
11. In a system for charging elongated furnaces, a receiving hopper for a body of the material, a furnace of greater horizontal extent than said hopper, and means for transferring the body of material from said hopper to said furnace, whereby the horizontal extent of said body is progressively increased.
12. In a system for charging elongated furnaces, a receiving hopper for a body of the material, a furnace of greater horizontal extent than said hopper, and devices for successively transferring the body of material from said hopper to said furnace,
- whereby the horizontal extent of said body is progressively increased in successive steps.
13. In a system for charging elongated furnaces, a gathering car having a number of compartments, and a cooperating charge car having corresponding compartments and of greater horizontal extent than said gathering car.
14. In a system for charging elongated furnaces, a pair of receiving hoppers, a cooperating gathering car having compartments corresponding to but of greater horizontal extent than said hoppers, and a cooperating charge car having compartments corresponding to but of greater horizontal extent than the gathering car.
15. In a system for charging elongated furnaces, a pair of receiving hoppers, a cooperating gathering car having compartments corresponding to but of greater horizontal extent than said hoppers, a cooperating charge car having compartments corresponding to but of greater horizontal extent than the gathering car, and a cooperating furnace having a greater horizontal extent than said charge car.
16. In a system for charging elongated furnaces, a track leading to a discharge point at the furnace, a series of receiving hoppers along said track, a gathering car of greater horizontal extent than a hopper and movable on said track in order to receive the material from said hoppers, and a charge car of greater horizontal extent than and receiving the material from said gathering car.
17. In a system for charging elongated furnaces, a track leading to a discharge point at the furnace, a series of receiving hoppers along said track, a gathering car of greater horizontal extent than a hopper and movable on said track in order to receive the material from said hoppers, and a charge car of greater horizontal extent than and receiving the material from said gathering car, said charge car being of less horizontal extent than and adapted to deposit the material in the furnace.
18. In a system for charging elongated furnaces, an inclined main track leading to the furnace, a charge car thereon, an elevated track, a reserve charge car thereon, and a switch adapted to connect said elevated track with said main track.

In testimony whereof I affix my signature
this 19th day of June, 1922.

WILLIAM E. NEWNAM.

6. In a system for charging elongated furnaces, a weighing device comprising a number of hoppers, a gathering car adapted to receive the material from said device, said car having compartments corresponding to said hoppers, and a charge car adapted to receive the material from said gathering car, said charge car having compartments corresponding to the compartments in said gathering car.
7. In a system for charging elongated furnaces, a gathering car having compartments each of which is adapted to receive the material, and a charge car having compartments corresponding to the compartments in the charge car and adapted to receive the material therefrom.
8. In a system for charging elongated furnaces, a gathering track, a cross track leading to the furnace, a gathering car on said gathering track and having compartments each of which is adapted to receive the material, and a charge car on said cross track and having compartments corresponding to the compartments in the charge car and adapted to receive the material therefrom.
9. In a system for charging elongated furnaces, a receiving hopper for the material, a gathering car of greater horizontal extent than said hopper and adapted to receive the material therefrom, and a charge car of greater horizontal extent than said gathering car and adapted to receive the material therefrom.
10. In a system for charging elongated furnaces, a receiving hopper for the material, a gathering car of greater horizontal extent than said hopper and adapted to receive the material therefrom, a charge car of greater horizontal extent than said gathering car and adapted to receive the material therefrom.
11. In a system for charging elongated furnaces, a receiving hopper for a body of the material, a furnace of greater horizontal extent than said hopper, and means for transferring the body of material from said hopper to said furnace, whereby the horizontal extent of said body is progressively increased.
12. In a system for charging elongated furnaces, a receiving hopper for a body of the material, a furnace of greater horizontal extent than said hopper, and devices for successively transferring the body of material from said hopper to said furnace,
- whereby the horizontal extent of said body is progressively increased in successive steps.
13. In a system for charging elongated furnaces, a gathering car having a number of compartments, and a cooperating charge car having corresponding compartments and of greater horizontal extent than said gathering car.
14. In a system for charging elongated furnaces, a pair of receiving hoppers, a cooperating gathering car having compartments corresponding to but of greater horizontal extent than said hoppers, and a cooperating charge car having compartments corresponding to but of greater horizontal extent than the gathering car.
15. In a system for charging elongated furnaces, a pair of receiving hoppers, a cooperating gathering car having compartments corresponding to but of greater horizontal extent than said hoppers, a cooperating charge car having compartments corresponding to but of greater horizontal extent than the gathering car, and a cooperating furnace having a greater horizontal extent than said charge car.
16. In a system for charging elongated furnaces, a track leading to a discharge point at the furnace, a series of receiving hoppers along said track, a gathering car of greater horizontal extent than a hopper and movable on said track in order to receive the material from said hoppers, and a charge car of greater horizontal extent than and receiving the material from said gathering car.
17. In a system for charging elongated furnaces, a track leading to a discharge point at the furnace, a series of receiving hoppers along said track, a gathering car of greater horizontal extent than a hopper and movable on said track in order to receive the material from said hoppers, and a charge car of greater horizontal extent than and receiving the material from said gathering car, said charge car being of less horizontal extent than and adapted to deposit the material in the furnace.
18. In a system for charging elongated furnaces, an inclined main track leading to the furnace, a charge car thereon, an elevated track, a reserve charge car thereon, and a switch adapted to connect said elevated track with said main track.

In testimony whereof I affix my signature this 19th day of June, 1922.

WILLIAM E. NEWNAM.

Certificate of Correction.

It is hereby certified that in Letters Patent No. 1,551,606, granted September 1, 1925, upon the application of William E. Newnam, of St. Louis, Missouri, for an improvement in "Furnace-Charging Systems," an error appears in the printed specification requiring correction as follows: Page 3, line 79, claim 1, after the word "to" insert the words *a discharge point at*; and that the said Letters Patent should be read with this correction therein that the same may conform to the record of the case in the Patent Office.

Signed and sealed this 27th day of October, A. D. 1925.

[SEAL.]

KARL FENNING,
Acting Commissioner of Patents.
